US00D745558S

(12) **United States Design Patent**
Clarke et al.

(10) **Patent No.:** **US D745,558 S**
(45) **Date of Patent:** **** Dec. 15, 2015**

(54) **DISPLAY SCREEN OR PORTION THEREOF
WITH ICON**

(71) Applicant: **Apple Inc.**, Cupertino, CA (US)

(72) Inventors: **Graham Clarke**, Mountain View, CA (US); **Matt Evans**, San Francisco, CA (US); **Paul Lopez**, Los Gatos, CA (US); **Henrique Penha**, San Francisco, CA (US); **Samuel Morgan Roberts**, San Francisco, CA (US); **Andre Souza Dos Santos**, Santa Clara, CA (US)

(73) Assignee: **Apple Inc.**, Cupertino, CA (US)

(**) Term: **14 Years**

(21) Appl. No.: **29/470,457**

(22) Filed: **Oct. 22, 2013**

(51) LOC (10) Cl. **14-04**

(52) U.S. Cl. **D14/492**
USPC

(58) **Field of Classification Search**

USPC D14/485-495
CPC G06F 3/048; G06F 3/04817; G06F 3/0482

CLAIM

The ornamental design for a display screen or portion thereof with icon, as shown and described.

DESCRIPTION

The FIGURE is a front view of a display screen or portion thereof with icon showing our new design.

The broken lines around the FIGURE show a display screen or portion thereof and form no part of the claimed design.

1 Claim, 1 Drawing Sheet
